[57] CLAIM

The ornamental design for a combined hook holder and rod mover for spinal surgery, as shown and described.

DESCRIPTION

FIG. 1 is a perspective view of a combined hook holder and rod mover for spinal surgery;

FIG. 2 is a rear view of the combined hook holder and rod mover for spinal surgery of FIG. 1;

FIG. 3 is a front view of the combined hook holder and rod mover for spinal surgery of FIG. 1;

FIG. 4 is a side view of the combined hook holder and rod mover for spinal surgery of FIG. 1;

FIG. 5 is a side view of the combined hook holder and rod mover for spinal surgery of FIG. 1;

FIG. 6 is a top view of the combined hook holder and rod mover for spinal surgery of FIG. 1; and,

FIG. 7 is a bottom view of the combined hook holder and rod mover for spinal surgery of FIG. 1.

The broken line showing of the handle in FIGS. 1-6 is for illustrative purposes only and forms no part of the claimed design.
